United States Patent Office.

GEORGE W. EVERHART, OF LOUISVILLE, KENTUCKY.

Letters Patent No. 98,045, dated December 21, 1869.

FIRE-PLACE GRATE.

The Schedule referred to in these Letters Patent and making part of the same.

To all whom it may concern:

Be it known that I, GEORGE W. EVERHART, of Louisville, in the county of Jefferson, and State of Kentucky, have invented a new and useful Improvement in Fire-Grates; and I do hereby declare that the following is a full, clear, and exact description thereof, which will enable others skilled in the art to make and use the same, reference being had to the accompanying drawings, forming part of this specification.

This invention relates to improvements in that class of fire-grates used for heating rooms; and

It consists in so arranging them as to provide a clear air-space between the basket and the walls of the fire-place, both at the back and ends, for the admission of air more directly at these parts, for the better combustion of the coal and the gases arising therefrom.

It also consists in providing a recess in the hearth or bottom of the fire-place, under the grate, for the reception of ash-pans of greater capacity than can be contained on the top of the hearth, whereby a much larger quantity of cinder and ashes may be received and retained, so that less frequent removals of the same will be required.

Figure 1 is a transverse sectional elevation of my improved grate, and

Figure 2 is a horizontal section of the same.

Similar letters of reference indicate corresponding parts.

A represents the basket of iron rods or bars, which,

instead of being open at the ends and back, as in the usual way, and fitting snugly against the same, I make narrower and shorter than the space in the brick-work, and with ends and back of similar or suitable construction of iron bars or rods, to confine the coal at the said ends and back, and provide the free space B thereat, whereby the air may have free access to the fire behind, for the better supply of oxygen, and thereby to cause more perfect combustion.

C is the recess in the hearth or bed-plate under the grate, and

D, the large ash-pan.

By means of this recess the capacity of the pan may be largely increased, and thereby require less frequent removal.

Having thus described my invention,

I claim as new, and desire to secure by Letters Patent—

1. The arrangement of the grate-basket A, with the wall of the fire-place, to provide the air-space at the ends and the rear, substantially as specified.

2. The arrangement of the recess C and ash-pan, D in the hearth or bed, substantially as specified.

The above specification of my invention signed by me, this   day of   , 1869.

GEO. W. EVERHART.
